RECORDED.

UNITED STATES PATENT OFFICE.

PAUL JONES, OF COEYMAN'S, AND JOHN E. BURLINGHAM, OF NEW BALTIMORE, NEW YORK.

STREET-SWEEPING MACHINE.

SPECIFICATION forming part of Letters Patent No. 436,499, dated September 16, 1890.

Application filed March 10, 1890. Serial No. 343,322. (No model.)

To all whom it may concern:

Be it known that we, PAUL JONES, of Coeymans, in the county of Albany and State of New York, and JOHN E. BURLINGHAM, of New Baltimore, in the county of Greene and State of New York, have invented new and useful Improvements in Street-Sweeping Machines, of which the following is a specification, reference being had to the accompanying drawings, which form part of this specification, in which—

Figure 1 is a side elevation of a machine embodying our invention in proper condition for sweeping. Fig. 2 is a plan view of the same. Fig. 3 is a rear elevation; and Fig. 4 is a side elevation of the brush-operating and dirt-elevating mechanisms detached from the dirt-cart on which the forward part of said mechanism is borne.

Our invention relates to a street-sweeping machine, which comprises a dirt-cart on which the forward part of the mechanism for sweeping and elevating the dirt is borne, and which is detachable from said mechanism, so as to be utilized for the removal of the dirt to a dumping-ground; and the object of our invention is to combine in one construction the means for sweeping the street and carrying away the dirt collected therefrom.

As represented in the drawings, A designates a dirt-cart of any ordinary construction, excepting that each of its wheels 1 is provided with a sprocket-wheel 2, which is preferably secured to the hub of said cart-wheel, so as to rotate therewith.

B is the frame-work for the sweeping-brush and dirt-elevating mechanisms. Said frame is detachably connected to the dirt-cart A by means of a pair of arms 3, which extend along the opposite sides of the dirt-receptacle of said cart, and are secured thereto by means of hasps 4 or other suitable fastenings, which can be readily unfastened to release the cart from said frame-work. The rearward part of the latter is provided with a trailing wheel C, which is journaled in the outer end of the rearwardly-bent bifurcated arm D. The inner end of said arm is provided with a vertical pivot 5, which is fitted to revolve and to slide vertically in a bearing 6, fixed on said

frame-work. The center line of the axis of the trailing wheel C and the center line of the pivot 5 are arranged eccentrically to each other, so that the trailing wheel C will be automatically deflected to correspond to the course—straight or devious—in which the machine may be moved. The pivot 5 is provided with a circumferential flange 7, on which the weight of the rearward portion of the frame-work and its attached parts will bear whenever the sweeping mechanism is in operation. Said flange is also fitted to receive the pressure from an eccentric 8, which is pivoted to the bearing 6 for the pivot 5, and, when preferred, a pair of said eccentrics may be arranged at opposite sides of said bearing to bear on said flange. By turning said eccentrics so as to bring the larger side to bear upon said flange the rearward end of the machine may be raised to keep the brush from the surface of the street, and thereby the sweeping mechanism can be rendered inoperative whenever occasion may require. Each eccentric 8 is provided with an arm 9, by which it may be turned on its pivotal center, and said arm is connected to an operating-rod 10, by which said eccentrics can be manipulated by the driver of the machine when occasion requires.

The frame-work B is provided with an adjustable strut 11, of which there should be one at each side of the machine, and said strut or its equivalent should be arranged to carry the weight of the forward part of said frame-work and its attached mechanism whenever the dirt-cart A is detached therefrom; but when said dirt-cart is attached to the frame-work B said strut should be raised or swung up so that the frame-work B will have its forward end borne on said dirt-cart.

E designates a rotating brush by which the sweeping is effected. Said brush is made cylindrical in form, and is preferably composed of steel wire, which may be formed in tufts which are arranged spirally on the surface of said cylinder. The shaft 12 of said brush is journaled in adjustable bearings 13, which are fitted to slide in guides 14 on the sides of the frame-work B. Said bearings are connected by adjusting-screws 15 with like

bearings 16 for the shaft of a spur-wheel, hereinafter described, and the bearings 13 and 16 are arranged to be adjusted in the guides 14 simultaneously by means of the adjusting-screws 15, which pass through a flange 17 at the upper end of the guides 14, and are there provided with adjusting-nuts 18 above and below said flange. The outer end of the shaft 12 is provided with a pinion 19, which gears into a spur-wheel 20, hereinbefore referred to, which is secured to a shaft 17, which is journaled in the bearings 16. Said shaft has a sprocket-wheel 21 secured thereto. Said sprocket-wheel is connected by means of an endless chain 22 with the sprocket-wheel 2, so as to impart the required rotatory motion to the brush E.

F designates the dirt elevator or conveyer, which consists of an endless belt or belts provided with buckets 23, by which the dirt delivered by the brush E into said buckets is automatically deposited into the box or dirt receptacle of the cart A. Said elevator has its motion imparted thereto by means of an endless chain 24, which engages with the sprocket-wheel 2, which is attached to the wheel 1 on the opposite side of the cart A to the one which imparts motion to the endless chain 22. The latter connects with a sprocket-wheel 25, which is secured to a shaft 26, journaled in the upper part of the frame-work B. Said shaft also carries a drum 27, which is located to lie directly over the after part of the box of the cart A, so that the dirt delivered from the elevator-buckets will fall directly into the box of said cart. From the drum 27 the endless belt of the elevator passes over a pair of pulleys 28, which are secured to a shaft 29 and are spaced apart sufficiently to allow the length of the buckets 23 to pass between them. From the pulleys 28 the elevator-belt passes downwardly and under a drum 30, thence upwardly to the drum 31, from whence it passes to and over the upper side of the drum 27.

The drum 30 is journaled in the lower end of a pair of pendulous arms 32, whose upper end is pivoted, as at 33, to the frame-work B. The lower end of said arms is provided with a journal-box 34, which is adjustable thereon so as to produce an equal strain on both edges of the elevator-belt. The drum 30 is arranged in advance of but in proximity to the brush E, so that the dirt that is swept up by said brush will be delivered into the buckets 23 of the elevator. The drum 31 is journaled in the upper part of the rearward side of the frame-work B, but on a lower plane than the

journals of the drum 27, so that the elevator-belt will be carried on an inclined line from the drum 31 to the drum 27, thereby avoiding the escape of the dirt from the buckets. The strut 11 is pivoted, as at 35, to the frame-work B, and hooks 36 or other fastenings are provided for holding said strut in its raised position.

Our invention operates in the following manner: The dirt-cart A and frame-work B being secured together, and the endless chains 22 and 24 being engaged on the sprocket-wheels respectively assigned to them, then as the machine is drawn over the roadway the brush E will be rotated and the dirt-elevator F will be set in motion, so that its buckets 23 will successively be brought into position in front of the brush E, where they will receive the dirt swept up by said brush, and this operation will be continued until the required load of dirt has been deposited in the dirt-cart. When this has been attained, the progress of the machine is stopped, the dirt-cart is disconnected from the sweeping mechanism and removed to any required place with but slight interruption to the operation, another dirt-cart is substituted for the one removed, the endless chains are connected to the sprocket-wheels, and the machine is ready for a continuance of its operation.

By constructing the buckets 23 of the dirt-elevator F of the same length as the revolving brush E we are enabled to deliver the dirt swept by said brush directly into said buckets, and by providing independent driving mechanisms for said elevator and brush we are enabled to rotate the latter, when required to effect a loosening up of the compacted dirt, without operating the elevator.

What we claim as our invention, and desire to secure by Letters Patent, is—

The combination, with a frame-work provided with sweeping and elevating mechanisms, of a trailing wheel pivoted to said frame-work by means of a pivot provided with a circumferential flange, and an eccentric fitted to bear upon said flange and secured to a shaft journaled in said frame-work, said shaft being provided with an arm by which said eccentric can be operated to raise and lower the rear end of said frame-work, as and for the purpose herein specified.

PAUL JONES.
